UNDERGARMENT FOR WOMEN'S WEAR

Philip H. Robbins, New York, N. Y., assignor to
Poirette Corsets, Inc., New York, N. Y., a corporation of New York

Application June 8, 1935, Serial No. 25,662

2 Claims.

(Cl. 2—30)

This invention relates to an undergarment for women's wear and has for its object to provide, in a manner as hereinafter set forth, an undergarment having elastic means extending upwardly from its sides and throughout the upper end of its back providing when the garment is worn for exerting an equal pull at all points at the top of the garment resulting in snug yielding engagement throughout the shoulders, under the arms and back of the wearer and preventing the busts of the wearer from projecting from the garment under the arms.

A further object of the invention is to provide, in a manner as hereinafter set forth, an undergarment for women's wear having means whereby a practical low back portion is had, as well as a back portion which will snugly engage a hollow back of a wearer.

A further object of the invention is to provide, in a manner as hereinafter set forth, an undergarment having means common to the bust and back portions thereof to cause the snug fitting of such portions when the garment is worn.

A further object of the invention is to provide, in a manner as hereinafter set forth, an undergarment having yieldable means common to its back portion and sides of its bust portion to continuously cause a snug fitting of such portions when the garment is worn without discomfiture to the wearer.

A further object of the invention is to provide, in a manner as hereinafter set forth, an undergarment having a continuous yieldable means to insure, when the garment is worn, a continuous snug fit with respect to the shoulders, under the arms and back of the wearer without discomfiture.

A further object of the invention is to provide, in a manner as hereinafter set forth, an undergarment having a practical low back for snugly and yieldingly fitting the back of the wearer, especially when the back of the wearer is hollow.

Further objects of the invention are to provide, in a manner as hereinafter set forth, an undergarment for the purpose referred to which is simple in its construction and arrangement, strong, durable and thoroughly efficient for the purpose intended thereby.

It is to be understood that the term "undergarment" used herein is intended to be a generic term embracing the application of the invention to the use of the garment in the form of merely a brassière or in the form of a bathing suit, the principal or feature of snug yielding fit and sup-

port being adaptable as herein set forth, as well to women's garments of such type or class.

In the drawing:

Figure 1 is a rear elevation of the garment showing the position thereof with respect to a wearer.

Figure 2 is a side elevation of the garment showing the adaptation thereof with respect to a wearer.

Figure 3 is a fragmentary view, in rear elevation of the garment.

Figure 4 is a fragmentary view, in side elevation of the garment.

Figure 5 is a section on line 5—5, Figure 4, and

Figure 6 is a sectional detail showing the elastic element prior to anchoring of the ends, only one of its ends being shown.

The garment generally indicated at 1 includes a bust portion 8, a front portion 9 to the upper end of which is secured to bust portion 8, a pair of side portions 10, 11 and a back portion 12. The garment 1 is shown as being positioned upon the simulation of a wearer indicated as 12a.

The garment further includes a continuous elastic element or member 13 of strap-like form 25 having a substantially semi-oval shaped central stretch 14, a pair of oppositely disposed upstanding incurved outer stretches 15, 16 of substantially convexo-concave contour, and a pair of oppositely disposed depending outcurved inner stretches 17, 18 of substantially concavo-convex contour.

The ends of the stretch 14 merge into the lower ends of the stretches 15, 16. The upper ends of the stretches 17, 18 merge into the upper ends of the stretches 15, 16 respectively. The lower end terminal portions 19, 20 of the stretches 17, 18 respectively are positioned against the inner face of stretch 14 in proximity to the points of emergence of the latter with the lower ends of the stretches 15, 16. The stretches 15, 17 are oppositely disposed with respect to each other. The stretches 16, 18 are oppositely disposed with respect to each other. The lower end terminal portions 19 of the stretches 17, 18 are anchored to the inner face of stretch 14. The stretches 15, 16 are of less length than that of the stretches 17, 18. The stretches 15, 17 in connection with end portion 21 of stretch 14 provide a closed substantially elliptical shaped loop 22. The stretches 16, 18 in connection with the end portion 22a of stretch 14 provide a closed substantially elliptical shaped loop 23. The loops 22, 23 incline towards each other from their lower to their upper ends.

The stretch 14 extends throughout the top edge of back portion 12 and upon the rear part of each

of the top of the side portions 10, 11 and is secured to oppose the top edge of back portion 12 and the top edge of the rear part of the side portions 10, 11 by a row of stitching 24. The stretches 15, 16 at their front edges are secured by any suitable means to the sides of the bust portion 8. The stretches 15, 16 extend above the bust portion 8. The stretches 17, 18 extend above the bust portion 8 and are free of connection to the garment other than their connection to the stretch 14.

The stretch 14 is for the purpose of causing the top of back portion 12 to yieldingly and snugly engage the back of the wearer and to enable the garment to be provided with a practical low back. The stretches 15, 16 are for the purpose of causing the sides of the bust portion 8 to yieldingly and snugly engage under the arms of the wearer and to prevent the busts from extending out under the arms. The portions 25, 26 of the stretches 15, 17 respectively coat to provide a yieldingly snugly fitting suspension for mounting on a shoulder of the wearer. The portions 27, 28 of the stretches 16, 18 respectively coat to provide a yieldingly snugly fitting suspension for mounting on the other shoulder of the wearer.

The element or member 13 will be of a length to provide for its use in connecting various waistline and shoulder lengths and is positioned for use in the desired relation with respect to the length of a waistline, the width of a back and length of the shoulders, and after so positioned, each end terminal portion thereof will appear as in Figure 6 as extended below stretch 14, as at 29. The stretches 17, 18 are then cut away and the edges provided by the cut-offs made flush with the bottom edge of stretch 14 as shown in Figure 4. The stretches 17, 18 are then anchored to the stretch 14 by the rows of stitching 30. The portions of the element 13 bordering its end edges are concealed by rectangular members 31. The members 31 are of a length greater than the width of the element 13 and have finished lengthwise edges as is shown in Figure 5. The members 31 are secured to the stretches 14, 17, 18 of the element 13 by the rows of stitching 32 and to stretch

14 of element 13 by rows of stitching 33 positioned adjacent to the side edges of stretches 17, 18. The element 13, relative to the bust, front, sides and back portions of the garment will then be of the arrangement shown in Figure 3. 5

What I claim is:

1. An undergarment including bust, front, sides and back portions, and a continuous elastic member of a strap-like form having an intermediate stretch secured to and throughout the top of said back portion and to the rear parts of the tops of said side portions, said member having a pair of upwardly extending outer stretches secured to and throughout the sides of said bust portion, and said member having a pair of inner stretches depending from said outer stretches and having their lower ends anchored to the intermediate stretch at spaced points of the latter, the said several stretches coacting to form a pair of up-standing spaced closed loops for connecting the garment to and for suspending it from the shoulders of the wearer. 15

2. An undergarment including bust, front, sides and back portions, and a continuous elastic member of strap-like form having an intermediate stretch secured to and throughout the top of said back portion and to the rear parts of the tops of said side portions, said member having a pair of upwardly extending outer stretches secured to and throughout the sides of said bust portion, and 30 said member having a pair of inner stretches depending from said outer stretches and having their lower ends anchored to the intermediate stretch at spaced points of the latter, the said several stretches coacting to form a pair of up-standing spaced closed loops for connecting the garment to and for suspending it from the shoulders of the wearer, and the said outer stretches extending above the bust portion and merging at 35 their upper ends into the upper ends of the inner stretches, the said intermediate stretch merging into the lower ends of the said outer stretches, and the said inner stretches extending above and depending below said bust portion.

PHILIP H. ROBBINS. 45
